DECANTER

William F. Wood, Alhambra, Calif., assignor to Knudsen Corporation, Los Angeles, Calif., a corporation of California

Filed Sept. 19, 1969, Ser. No. 19,225

Term of patent 14 years

Int. Cl. D9—01

U.S. Cl. D9—92

FIG. 1 is an elevational view of a decanter showing my new design, the opposite side being the same in appearance;

FIG. 2 is a plan view looking in the direction of the arrows 2—2 of FIG. 1; and

FIG. 3 is a sectional view taken on the line 3—3 of FIG. 1 with the body portions of the bottle being omitted for convenience of illustration.

I claim:

The ornamental design for a decanter, as shown and described.
